BASIC DYESTUFFS

Bruno J. R. Nicolaus, Basel, Switzerland, assignor to
Sandoz Ltd., Basel, Switzerland
No Drawing. Filed Jan. 18, 1960, Ser. No. 7,968
Claims priority, application Switzerland Jan. 28, 1959
6 Claims. (Cl. 260—158)

The importance of the polyacrylonitrile fibers has greatly increased in recent years and has led to intensive research in dyestuff chemistry with the object of discovering new dyestuffs for these fibers and practical methods of application. The principal dyeing methods for polyacrylonitrile fibers are

- (a) The cuprous ion method for dyeing with acid dyestuffs,
- (b) The dyeing method with disperse dyestuffs,
- (c) The dyeing method with basic dyestuffs.

Disperse dyestuffs give only light shades on polyacrylonitrile fibers and, even so, only a comparatively small number of the dyestuffs of this class are suitable. By means of the cuprous ion method it is possible to produce heavier shades, but its practical application is rather too complicated for the textile colorist. Dyeing with basic dyestuffs, however, has the advantage of being a relatively simple method of application and it gives dyeings of high all-round fastness, in particular of excellent wet fastness and very good light fastness. For these reasons the basic dyestuffs have become the preferred class for polyacrylonitrile fibers, though at the same time they have the great disadvantage that it is very difficult to obtain level dyeings and prints with them, especially in the case of light shades.

Most of the well drawing basic dyestuffs possess such high affinity for polyacrylonitrile fibers by virtue of their positive charge that they are taken up by the fiber much too rapidly. In consequence the dyed goods have a flecked appearance and are of no further value for practical use. This undesirable effect is a very great obstacle to successful dyeing, especially as the unlevel dyeings given by basic dyestuffs on polyacrylonitrile fibers cannot be stripped or topped satisfactorily.

The surprising discovery has now been made that basic dyestuffs which contain at least one aminoxide group possess good affinity for polyacrylonitrile fibers at temperatures below 100° C. and therefore are very well suited for the dyeing and printing of shaped articles of polyacrylonitrile or of copolymers and other materials which contain polyacrylonitrile as the essential component.

These dyestuffs combine the advantages of the basic dyestuffs (high affinity for polyacrylonitrile fibers, excellent light and wet fastness) with those of the disperse dyestuffs (excellent level dyeing at all depths, even the lightest shades).

The mechanism of dyeing on polyacrylonitrile fibers with the dyestuffs containing aminoxide groups probably involves the formation of a salt, in which the aminoxide group acts as a cation and combines with the acid groups present in the polyacrylonitrile. This hypothesis is supported by the following experiment. When a polyacrylonitrile fiber is treated with a cationic agent prior to dyeing it loses its capacity for absorbing basic dyestuffs (it is then called "blocked polyacrylonitrile"), while it can still be dyed with disperse dyestuffs which are only dissolved and diffused in the fiber.

In contrast to the normal disperse dyestuffs, the dyestuffs containing aminoxide groups do not dye blocked polyacrylonitrile but behave in this respect like basic dyestuffs.

Owing to the semi-polar oxygen linkage the basic character of the nitrogen atom in the aminoxide group of the

2

disclosed dyestuffs is considerably weakened; as a result of this reduced basicity they level considerably better than the corresponding oxygen-free dyestuffs.

This invention relates to new basic dyestuffs sulfonic acid groups, free from carboxylic acid and which contain at least one grouping of the general formula

wherein:

X denotes the direct linkage, an oxygen atom or a nitrogen atom substituted by a hydrogen atom or an organic radical,

R₁ a divalent organic radical, and

R₂ and R₃ each a monovalent organic radical or together with N a heterocyclic ring.

The process for the production of the new basic dyestuffs consists in converting a tertiary amine of the formula

wherein:

A₁ denotes the radical free from carboxylic acid or sulfonic acid groups of a dyestuff or of a compound capable of dyestuff formation and X, R₁, R₂ and R₃ possess the aforeslated meanings into the aminoxide compound by treatment with an oxidizing agent and converting this compound, when A₁ represents the radical of a compound capable of dyestuff formation, into a dyestuff by a suitable reaction.

The following are enumerated as examples of suitable dyestuff radicals: radicals of the anthraquinone, phthalocyanine, triphenylmethane, cyanine, perinone, naphthoquinone, nitro, oxazine, thiazine, indigo, quinophthalone and, in particular, those of the azo dyestuff series. The compounds capable of dyestuff formation are preferably those which can be converted into azo dyestuffs by reaction with a diazonium salt, or compounds which contain a diazotizable amino group or a substituent capable of conversion into such a group and upon diazotization can be coupled with a coupling component, further those which can be converted into dyestuffs by condensation. The azo coupling reaction is accomplished by the known method, preferably in a weakly alkaline to acid medium which may be buffered if necessary.

The reaction of the tertiary amine with the oxidizing agent to give the corresponding aminoxide compound is conducted preferably in an inert solvent or, if necessary, in aqueous suspension or solution, preferably at elevated temperature and with an excess of oxidizing agent.

Examples of suitable solvents are alcohols, such as methanol, ethanol, propanol, isopropanol, ketones such as acetone, methylethyl ketone, acetic acid esters and other esters, formic acid, acetic acid and propionic acid. Suitable oxidizing agents are e.g. hydrogen peroxide, chromic acid, per acids (peracetic acid, persulfuric acid), per salts (persulfates, perborates, percarbonates), the various manganese oxides and nitric acid, nitrous oxides, halogens and hypohalogenites. Also, the technique of anodic oxidation can be employed.

The basic dyestuffs formed are separated by one of the standard basic operations such as filtration, evaporation and filtration, precipitation with a suitable agent and filtration.

The new basic dyestuffs are suitable for the production of full shades by dyeing and printing processes on materials composed of polymers containing more than 80% acrylonitrile such as polyacrylonitrile, e.g. Orlon (regis-

tered trade mark) and copolymers of 95% acrylonitrile and 5% vinyl acetate or methyl acrylate or methyl methacrylate.

The dyestuffs containing a group of Formula I as well as their salts are applied to best advantage form aqueous, preferably weakly acid, suspension at high temperature, preferably in presence of dispersing agents of non-ionic, anionic or cationic character. The dyestuffs are equally suitable for application by higher temperature processes in closed dyeing machines under pressure. The dyeings and prints obtained on polyacrylonitrile materials possess good fastness to light, washing, water, milling, perspiration, sea water, pleating and heat setting, and even in the lightest depths they are very level.

With the dyestuffs conforming to the definition blended fabrics containing polyacrylonitrile fiber as one of the components can be successfully dyed while the wool, cotton or viscose in the blend is reserved.

The new dyestuffs also have affinity for synthetic polyamide fibers, e.g. "Perlon," "Rilsan" (registered trademarks), nylon; cellulose ester fibers, e.g. cellulose acetate and cellulose triacetate; and terephthalic acid ester fibers, e.g. "Terylene," "Dacron" (registered trademarks), on which they give yellow, orange, red, violet or blue shades. On these fibers also they possess excellent fastness to light, washing, water, sea water, perspiration, pleating, pressing, heat setting, gas fumes and chlorine, and a number of them are dischargeable to white. They reserve cotton, viscose and wool to a great extent and in cases where slight staining of these fibers occurs it can be largely cleared by treatment with hydrosulfite. Certain of the new dyestuffs are suitable for the coloration of lacquer media, oils, synthetic resins and man-made fibers in the mass.

In the following examples the parts and percentages are by weight and the temperatures in degrees centigrade. The melting points are uncorrected.

EXAMPLE 1

20 parts of the tertiary amine of the formula

are dissolved in 20 parts of ethyl alcohol and reacted with 20 parts of 34% hydrogen peroxide at 60°. On completion of oxidation, which can be followed by observing the consumption of the oxidizing agent, the reaction mass containing the crude aminoxyde compound is evaporated almost to dryness. 300 parts of water and 12 parts of 30% hydrochloric acid are added to give a clear solution which is added to a previously prepared diazo solution of 14 parts of 1-amino-4-nitrobenzene, 30 parts of 30% hydrochloric acid, 200 parts of water and 7 parts of sodium nitrite at 5°. On completion of coupling, which can be accelerated by the addition of sodium acetate, the precipitated red dyestuff chlorohydrate is filtered off, washed neutral and dried. The crude product which is obtained in excellent yield melts at 169-170° and is practically pure. If desired, it can be recrystallized from glacial acetic acid, upon which it melts at 175°. In this way a dyestuff of low solubility in water is obtained which dyes polyacrylonitrile fibers from aqueous acetic acid suspension in level red shades of good fastness to light, washing, perspiration, sublimation, pleating, pressing, water, sea water, gas fumes and bleaching.

When the 14 parts of 1-amino-4-nitrobenzene in Example 1 are replaced by 17.5 parts of 1-amino-2-chloro-4-nitrobenzene, a dyestuff is obtained which crystallizes out of glacial acetic acid in the form of red needles with a melting point at 159-160°. The elementary analysis gives the values calculated for the hydrochloride.

When the 14 parts of 1-amino-4-nitrobenzene in Ex-

ample 1 are replaced by 13 parts of 1-amino-4-chlorobenzene, a dyestuff is obtained which crystallizes from glacial acetic acid in fine orange needles with a melting point at 155-156°. Here also the analysis gives the values calculated for the hydrochloride.

When the 14 parts of 1-amino-4-nitrobenzene in Example 1 are replaced by 20 parts of 1-amino-4-dimethylaminosulfonylbenzene, a dyestuff is obtained which crystallizes out of glacial acetic acid in attractively formed yellow chips with a melting point at 147-148°. The elementary analysis gives the values calculated for the hydrochloride.

Dyeing Example (a)

The following procedure is used for dyeing polyester fibers. A dyebath is prepared with 3000 parts of water, 10 parts of emulsified chlorobenzene and 0.5 part of a dyeing preparation made by intimately grinding 35 parts of the dyestuff of Example 1 paragraph 1, with 20 parts of sodium dinaphthylmethane-disulfonate, 20 parts of a fatty alcohol sulfonate and 25 parts of anhydrous sodium sulfate. At room temperature 100 parts of the polyethylene-terephthalate fiber "Dacron" are entered into the bath, the temperature increased to 100° and this temperature maintained for 1 hour. The goods are then removed, rinsed with water and dried. The scarlet dyeing obtained is fast to light, washing and pleating. Wool is to a great extent reserved and the slight stain which is left can be easily cleared with hydrosulfite.

Cellulose acetate is dyed as follows. A dyebath is prepared with 1 part of the aforescribed dyeing preparation, 6 parts of a fatty alcohol sulfonate and 3000 parts of water. 100 parts of cellulose acetate are entered at room temperature, the dyebath heated to 80° in 1 hour and held at this temperature for a further hour. After this time the dyeing process is completed. The goods are removed, rinsed and dried. The scarlet dyeing is fast to light, gas fumes and washing and can be discharged to white.

Dyeing Example (b)

A suitable procedure for dyeing polyacrylonitrile fibers is as follows. 35 parts of the dyestuff obtained according to Example 1 and 65 parts of dextrin are intimately ground to give a dyeing preparation, 1 part of which is suspended in 3000 parts of water at room temperature and the suspension acidified with 5 parts of acetic acid. 100 parts of a scoured fabric of polyacrylonitrile fiber is entered at 50°, the dyebath brought to the boil in 30 minutes and dyeing continued at this temperature for 1 hour. The dyed fabric is subsequently rinsed, soaped for 20 minutes in a boiling bath containing 1 gram per liter of a non-ionic detergent, rinsed and dried. A deep red dyeing of good fastness to light, washing, water, milling, perspiration, sea water, pleating and heat setting is obtained.

EXAMPLE 2

22 parts of the amine of the formula

are dissolved in 20 parts of ethyl alcohol and reacted with 20 parts of 34% hydrogen peroxide. On completion of oxidation, which can be followed from the consumption of the oxidizing agent and the increasing water-solubility of the product, the reaction mass containing the crude aminoxyde compound is diluted with 200 parts of water and added to a previously prepared diazo solution of 18.5 parts of 1-amino-2,4-dinitrobenzene, 80 parts of concentrated sulfuric acid, 7 parts of sodium nitrite and 240 parts of ice. By the addition of 40 parts of sodium acetate the coupling reaction is completed. The precipitated red dyestuff is filtered off, washed and dried. In the crude

state it melts at 161-163° and dyes polyacrylonitrile fibers in violet shades.

When 1-diazo-2,4-dinitrobenzene is coupled with the coupling component used in Example 1 which has the formula

another violet dyestuff is obtained with melting point 10 129-132°.

EXAMPLE 3

The dilute solution of the coupling component obtained according to the particulars given in Example 2 is added to a previously prepared diazo solution of 21 parts of 1-amino-2,6-dichloro-4-nitrobenzene, 80 parts of concentrated sulfuric acid, 7 parts of sodium nitrite and 240 parts of ice. Coupling is completed by the addition of 40 parts of sodium acetate, and the precipitated brown dyestuff is filtered off, washed and dried. In the crude state it melts at 152-154° and dyes polyacrylonitrile fibers in deep red-brown shades.

When 1-diazo-2,6-dichloro-4-nitrobenzene is coupled with the coupling component used in Example 1, a yellow-brown dyestuff is obtained which melts in the crude state at 110-111°.

EXAMPLE 4

27 parts of the tertiary amine of the formula

are reacted in 20 parts of methyl or isopropyl alcohol with 40 parts of 34% hydrogen peroxide at 60°. On completion of oxidation, which can be observed from the consumption of the oxidizing agent and the increasing water-solubility of the product, the reaction mass is diluted with 200 parts of water and added to a previously prepared diazo solution of 17.5 parts of 1-amino-2-chloro-4-nitrobenzene, 30 parts of 30% hydrochloric acid, 200 parts of water and 7 parts of sodium nitrite at 5°. On completion of coupling, which can be accelerated by the addition of sodium acetate, the precipitated red dyestuff chlorohydrate is filtered off, washed neutral and dried.

The crude product, which is obtained in excellent yield, melts at 125-126° and is practically pure. It dyes polyacrylonitrile fibers in scarlet shades of very good fastness properties.

5 In place of the 27 parts of the tertiary amine used above, equivalent amounts of the tertiary amines listed below can be employed to give other scarlet dyestuffs with similar dyeing properties.

	Coupling Compound	M.P. of Crude Dyestuff, degrees
15	$\text{C}_6\text{H}_5\text{N}(\text{CH}_2\text{CH}_2\text{N}(\text{CH}_3)_2)\text{CH}_2\text{CH}_3$	187-188
20	$\text{C}_6\text{H}_5\text{N}(\text{CH}_2\text{CH}_2\text{N}(\text{CH}_3)_2)\text{CH}_2\text{CH}_2\text{N}(\text{CH}_3)_2$	198-200
25	$\text{C}_6\text{H}_5\text{N}(\text{CH}_2\text{CH}_2\text{N}(\text{CH}_3)_2)\text{CH}_2\text{CH}_2\text{N}(\text{CH}_3)_2$	159-160
30	$\text{C}_6\text{H}_5\text{N}(\text{CH}_2\text{CH}_2\text{N}(\text{CH}_3)_2)\text{CH}_2\text{CH}_3\text{N}(\text{C}_2\text{H}_5)_2$	194-195

When the coupling component produced according to Example 2 is coupled with 1-diazo-4-nitrobenzene, using the process described in Example 4, a red dyestuff is obtained which melts at 118-120° and dyes polyacrylonitrile fibers in very bright red shades having excellent fastness properties.

Further valuable basic dyestuffs which can be produced according to the details given in Examples 1 to 4 are described in the following table; they correspond to the formula

Example No.	R_4	x	y	R_5	R_6	Shade of Dyeing on Polyacrylonitrile Fibers
5	4-nitrophenyl	H	H	Methyl	$-\text{CH}_2\text{CH}_2\text{NO}-(\text{CH}_3)_2$	Red.

EXAMPLE 66

20 parts of the tertiary amine of the formula

are dissolved in 20 parts of ethyl alcohol and reacted with 20 parts of 34% hydrogen peroxide at 60°. On completion of oxidation, which can be followed from the consumption of the oxidizing agent, the reaction mixture containing the crude aminoxyde compound is diluted with 50 parts of acetic acid. The clear solution obtained is added to a previously prepared diazo solution of 18 parts of 6-methoxy-2-aminobenzothiazole, 250 parts of 100% sulfuric acid, 250 parts of water and 7 parts of sodium nitrite at 5°. On completion of coupling, the reaction mass is charged onto 750 parts of ice and with vigorous stirring about 500 parts of 30% sodium hydroxide solution are added to adjust the pH value to 5. The precipitated red dyestuff is filtered off, washed neutral with dilute salt solution, and dried. The crude product is obtained in excellent yield and is practically pure. It dissolves in water with a fine red coloration and dyes polyacrylonitrile fibers by the process described in Dyeing Example b in level red shades of good fastness to light, washing, perspiration, sublimation, pleating, pressing, water, sea water, gas fumes and bleaching.

The new dyestuff has the formula

EXAMPLE 67

40 56 parts of the red dyestuff obtained according to Example 66 are dissolved in 1000 parts of chlorobenzene and 200 parts of methyl alcohol at boiling temperature. 40 parts of dimethyl sulfate are dropped into the clear red solution with vigorous stirring, upon which the solution rapidly changes color to blue.

45 After a short time quaternation is completed. The reaction mass is allowed to cool and the precipitate formed is filtered off, washed with chlorobenzene and dried.

50 The crude product is obtained in excellent yield and is practically pure. It dissolves in water with a brilliant blue coloration and in concentrated sulfuric acid with a yellow coloration. Applied to polyacrylonitrile fibers by the method described in Dyeing Example b, it gives brilliant blue shades of excellent fastness to light, washing, perspiration, pressing, water, sea water, gas fumes and bleaching, and reserves wool present in the dyebath. The dyes are very level, being markedly superior in this respect to dyes of the constitutionally similar dyestuffs produced from the same diazo compound and diethylaminobenzene as coupling component.

The new dyestuff has the formula

70 Further valuable basic dyestuffs which can be produced 75 according to the details given in Examples 66 and 67 are

described in the following table; they correspond to the formula

sulfonic acid and/or carboxylic acid groups or of free dyestuffs acids of 2:1 metal complex dyestuffs free from sulfonic and carboxylic acid groups; with these ions the resulting dyestuffs are insoluble both in water and organic solvents and are valuable for use as pigments.

Some of the coupling compounds used in the foregoing examples are new. They can be produced, for example,

In the foregoing table anion Θ denotes a Cl^- , Br^- , I^- , HSO_4^- , H_2PO_4^- , $\frac{1}{2}\text{SO}_4^-$, ZnCl_3^- , CH_3SO_3^- ,

$\text{C}_4\text{H}_9-\text{SO}_3^-$, $\text{CH}_3-\text{O}-\text{SO}_3^-$, $\text{C}_2\text{H}_5-\text{O}-\text{SO}_3^-$,

$\text{C}_6\text{H}_5-\text{SO}_3^-$, $\text{CH}_3-\text{C}_6-\text{H}_4-\text{SO}_3^-$ (ortho or para), $\text{Cl}-\text{C}_6\text{H}_4-\text{SO}_3^-$ (ortho or para), $\text{NO}_2-\text{C}_6\text{H}_4-\text{SO}_3^-$ (meta),

HCOO^- , CH_3-COO^- , $\text{C}_2\text{H}_5-\text{COO}^-$, $\text{C}_3\text{H}_7-\text{COO}^-$

$\text{Cl}-\text{CH}_2-\text{COO}^-$, $\text{C}_6\text{H}_5-\text{COO}^-$, the lactate, oxalate, tartrate or citrate ion. When produced with these ions the dyestuffs are sufficiently soluble in water to be applicable to polyacrylonitrile fibers from aqueous solution. Anion Θ can also represent a caproate, enanthate, caprylate, pelargonate, caprate, undecylate, laurate, myristate, palmitate, stearate, arachidate, oleate, elaidinate, erucate, linoleate or linolenate ion; in such cases the dyestuffs are less soluble in water but are soluble in organic solvents, e.g. acetone, methylene chloride and dimethyl formamide, and are suitable for dyeing cellulose acetate, cellulose triacetate and polyacrylonitrile in the mass, as well as polyacrylonitrile from aqueous dispersion. Finally, anion Θ can also represent a phosphotungstate, phosphomolybdate, phosphotungstomolybdate, silicomolybdate or silicotungstate ion or the anionic form of dyestuffs containing

from the corresponding hydroxy components according to the scheme

65 The tertiary amine of the formula

70 used in Example 1 can be produced, for example, as follows: 165 parts of N-ethyl-N-hydroxyethylaminobenzene are dropped into 153 parts of phosphorus oxychloride at 70-90°. When the reaction has run its course, which can be detected from the conclusion of the exothermic reaction, the liquid mass is run into a mixture of 400

parts of ice and 100 parts of water and the reaction mixture adjusted to the pH value of 5 by the addition of dilute sodium hydroxide solution. The precipitated oil is then separated and distilled with vacuum. Its boiling point is at 133-135° at 14 Torr. The yield is almost quantitative. 184 parts of the N-ethyl-N-chloroethyl-aminobenzene obtained and 400 parts of 40% dimethylamine solution are mixed in an autoclave for 20 hours at 140°. On cooling, the reaction mixture is drawn off in a separating funnel and the organic phase distilled with vacuum. Its boiling point is 85-86° at 0.03 Torr. The yield is practically quantitative.

The following table gives details of further valuable tertiary amines which can be produced according to the particulars presented in the foregoing.

Formula	Boiling Point, °C.	Pressure in Torr.
1-(N-ethyl-N-chloroethyl)-amino-3-methylbenzene	143-144	13-14
1-(N-ethyl-N-dimethylaminoethyl)-amino-3-methylbenzene	141-143	14-15
N,N-bis(chloroethyl)-aminobenzene	169-170	14-15
1-N,N-bis(chloroethyl)-amino-3-methylbenzene	180-182	13-14
1-N,N-bis(chloroethyl)-amino-3-chlorobenzene	198-200	13-14 25
1-(N-ethyl-N-diethylaminoethyl)-amino-3-methylbenzene	161-162	14
1-(N-isobutyl-N-chloroethyl)-amino-benzene	144-146	13-14
(N-methyl-N-chloroethyl)-amino-benzene	127-128	12-13
1-(N-ethyl-N-dibutylaminoethyl)-amino-3-methylbenzene	145-146	0.01
1-(N-isobutyl-N-dimethylaminoethyl)-amino-benzene	144-145	14-15 30
1-(N-methyl-N-dimethylaminoethyl)-amino-benzene	129-130	14-15
1-(N-ethyl-N-dimethylaminoethyl)-amino-3-bromobenzene	116-118	0.06
1-N,N-bis(dimethylaminoethyl)-amino-3-chlorobenzene	171-172	13-14 35
N,N-bis(dimethylaminoethyl)-amino-benzene	139-140	13-14
1-N,N-bis(dimethylaminoethyl)-amino-3-methylbenzene	98-94	0.1
N-ethyl-N-diethylaminoethyl-aminobenzene	159-160	13-14
1-(N-ethyl-N-2'-piperidinoethyl)-amino-3-methylbenzene	133-134	0.09
1-(N-ethyl-N-2'-morpholinoethyl)-amino-3-methylbenzene	152-155	0.02

EXAMPLE 110

26 parts of the tertiary amine of the formula

are dissolved in 20 parts of ethyl alcohol and reacted with 20 parts of 34% hydrogen peroxide at 60°. On completion of oxidation, which can be checked by observing the consumption of the oxidizing agent, the reaction mass containing the crude aminoxyde compound is evaporated to dryness with vacuum and added to 300 parts of water containing 12 parts of 30% hydrochloric acid. A clear solution is formed which is added to a previously prepared diazo solution of 17.5 parts of 1-amino-2-chloro-4-nitrobenzene, 30 parts of 30% hydrochloric acid, 200 parts of water and 7 parts of sodium nitrate at 5°. On completion of coupling, which can be speeded up by the addition of sodium acetate, the precipitated red dyestuff chlorohydrate is filtered off, washed neutral and dried. The crude product is obtained in excellent yield and high purity; it melts at 116-120°. It can be recrystallized if desired from glacial acetic acid to give a dyestuff of low water-solubility which dyes polyacrylonitrile fibers from aqueous colloidal solution in level red shades of excellent fastness properties.

When 1-diazo-2-chloro-4-nitrobenzene is coupled with the coupling component of the formula

a red dyestuff which melts at 135-140° is obtained.

The two following tables give details of further aminoxyde dyestuffs of the formulae

They are characterized in the tables by the symbols alkyl, R₁₀, R₁₁, R₁₂, R₁₃ and R₁₄ or R₁₅, R₁₆, and R₁₇ respectively, and by the shade of the dyeings obtained 50 with them on polyacrylonitrile fibers.

Example No.	Alkyl	R ₁₀	R ₁₁	R ₁₂	R ₁₃	R ₁₄	Shade of Dyeing on Polyacrylonitrile Fibers
111	Methyl	-(CH ₂) ₃ -HN-O ₂ S	H	Methyl	Ethyl	Ethyl	Yellow-orange.
112	do	-(CH ₂) ₃ -HN-O ₂ S	H	do	do	2'-cyanoethyl	Do.

142	do	—CH ₂ —CO—	Cl	4'-diethylaminophenyl	Do.	
143	do	—CH ₂ —CO—	Br	do	Violet.	
144	do	—CH ₂ —CO—	CF ₃	do	Do.	
145	do	—CH ₂ —CO—	NO ₂	do	Ruby.	
146	do	—CH ₂ —CO—	CN	do	Do.	
147	do	—CH ₂ —CO—	CH ₃ —SO ₂	do	4'-diethylamino-2'-methyl-phenyl	Red.
148	do	—CH ₂ —CO—	CN	do	Do.	
149	do	—CH ₂ —CO—	H	do	Do.	

Further examples are the dyestuffs of the formulae:

Nr.		
150-----		Yellow-orange.
151-----		Do.
152-----		Do.

EXAMPLE 153

1 part of a dyeing preparation made according to the description given in Example 1 and containing 35% of 40% of the dyestuff of the formula

polyacrylonitrile staple fiber yarn are immersed in the liquor at 50°. The machine is closed, the inside temperature increased to 130° and dyeing continued at this temperature for 30 minutes under pressure. A brilliant, level-dyed blue shade of high tintorial strength is obtained which shows excellent fastness properties.

Dyeings of similarly high all-round fastness are obtained with anthraquinone dyestuffs of, e.g., the following formula

is suspended in 3000 parts of water at room temperature with 5 parts of acetic acid. The suspension is run into a high temperature dyeing machine and 100 parts of

Example No.	R ₁₈	R ₁₉	R ₂₀	R ₂₁	R ₂₂	R ₂₃	R ₂₄	R ₂₅	Shade of Dyeing on Polyacrylonitrile Fibers
154	Amino	Cl	H	—NH—CH ₂ —CH ₂ —NO—(CH ₂ —CH ₃) ₂	H	H	H	H	Blue.
155	do	Br	H	—NH—CH ₂ —CH ₂ —NO—(CH ₂ —CH ₃) ₂	H	H	H	H	Do.
156	do	(R ₁₉ and R ₂₀ together)		Amino	H	H	H	H	Do.
				N—CH ₂ —CH ₂ —NO (—CH ₂ —CH ₃) ₂					
157	OH	H	H	—NH—CH ₂ —CH ₂ —NO—(CH ₂ —CH ₃) ₂	NO ₂	H	H	OH	Green-blue.
158	Amino	H	H	—NH— —SO ₂ —NH— CH ₂ —CH ₂ —NO(CH ₂ —CH ₃) ₂	H	H	H	H	Violet-blue.
159	OH	H	H	—NH— —CH ₂ CH ₂ NO— (CH ₂ —CH ₃) ₂	OH	H	H	NO ₂	Blue.
160	Amino	CF ₃	H	—NH—CH ₂ —CH ₂ —NO—(CH ₂ —CH ₃) ₂	H	H	H	H	Green-blue.

Example No.	R ₁₈	R ₁₉	R ₂₀	R ₂₁	R ₂₂	R ₂₃	R ₂₄	R ₂₅	Shade of Dyeing on Polyacrylonitrile Fibers
161	OH	H	H		NO ₂	H	H	OH	Green-blue.

EXAMPLE 162

1 part of the dyeing preparation made up as described in Example 1 with the dyestuff of the formula

is dispersed with 10 parts of acetic acid in 3000 parts of water at room temperature. 200 parts of a blended fabric containing 60% polyacrylonitrile fiber and 40% cotton are entered in the dyebath at 55° and dyed for 30 minutes at 125° under pressure. The synthetic fiber is dyed in a deep, level reddish-yellow shade while the cotton is reserved.

Dyeings having similar fastness properties are obtained when, for example, the following dyestuffs are used:

30

When polyacrylonitrile fabrics are dyed from a neutral

or weakly acid bath according to the details of Example 1 with a dyestuff of the formula

Example No.	R ₂₀	R ₂₇	R ₂₈	Shade of Dyeing on Polyacrylonitrile Fibers
163	-CH ₂ -CH ₂ -NO(-CH ₂ -CH ₃) ₂	H	H	Yellow.
164	-CH ₂ -CH ₂ -NO(-CH ₂ -CH ₃) ₂	-CH ₃	H	Do.
165	-CH ₂ -CH ₂ -NO(-CH ₂ -CH ₃) ₂	-C ₂ H ₅	H	Do.
166	-CH ₂ -CH ₂ -NO(-CH ₂ -CH ₃) ₂	-C ₂ H ₅	-CH ₃	Do.
167	-CH ₂ -CH ₂ -NO(-CH ₂ -CH ₃) ₂	-C ₂ H ₅	-O-C ₂ H ₅	Reddish-yellow.
168	-CH ₂ -CH ₂ -NO(-CH ₂ -CH ₃) ₂	-C ₂ H ₅	-O-CH ₃	Do.
169	-CH ₂ -CH ₂ -NO(-CH ₂ -CH ₃) ₂	-CH ₂ -CH ₂ -NO(-CH ₂ -CH ₃) ₂	H	Yellow.
	CH ₃			
170	-CH ₂ -CH ₂ -NO(-CH ₂ -CH ₃) ₂	-C ₂ H ₅	-CH ₃	Do.

Further the dyestuff of the formula:

EXAMPLE 172

30 parts of the dyeing preparation made as described in Example 1 with the dyestuff of the formula

is suspended with 50 parts of thioglycol and 10 parts of acetic acid in hot water and the suspension mixed with a gum tragacanth thickening 60:1000 to give 1000 parts of printing paste. This is applied to a fabric of poly-

or

or

or

or

17

deep, level yellow shades of excellent all-round fastness are obtained.

EXAMPLE 174

Very pleasing, level red prints are obtained by the process described in Example 172 with the dyestuff of the formula

The dyestuff of the formula

gives blue prints.

The dyestuff of the formula

applied according to the process described in Example 172 gives full, level orange prints with very good fastness properties.

Formulae of representative dyestuffs of the foregoing examples are as follows:

Having thus disclosed the invention what I claim is:

1. Basic dyestuff of the formula

wherein:
n is one of the numerals 1 and 2;
m is one of the numerals 0 and 1;
q is one of the numerals 0 and 1;
p is one of the numerals 0 and 1;
q being at most equal to *p*.

2. The basic dyestuff of the formula

3. The basic dyestuff of the formula

4. The basic dyestuff of the formula

5. The basic dyestuff of the formula

6. The basic dyestuff of the formula

UNITED STATES PATENT OFFICE
CERTIFICATE OF CORRECTION

Patent No. 3,119,809

January 28, 1964

Bruno J. R. Nicolaus

It is hereby certified that error appears in the above numbered patent requiring correction and that the said Letters Patent should read as corrected below.

Column 4, lines 60 to 63, the formula should appear as shown below instead of as in the patent:

columns 7 and 8, in the table, second column, line 6 thereof, for "nylbenzothiayzolyl-2" read -- nylbenzothiazolyl-2 --; columns 9 and 10, in the table, second column, line 34 thereof, for "N-methyltriazolyl-2-" read -- N-methylthiazolyl-2- --; columns 13 and 14, in the second table, second column, opposite Example No. 151, the right-hand portion of the formula should appear as shown below instead of as in the patent:

column 15, lines 60 to 67, the left-hand portion of the formula should appear as shown below instead of as in the patent:

Signed and sealed this 20th day of October 1964.
